(57) **CLAIM**

The ornamental design for a decorative air freshener, as shown and described.

DESCRIPTION

FIG. 1 is a front elevational view of the decorative air freshener of the present invention, the rear view being a mirror image thereof;

FIG. 2 is a left side elevational view of the decorative air freshener of FIG. 1;

FIG. 3 is a right side elevational view of the decorative air freshener of FIG. 1;

FIG. 4 is a top plan view of the decorative air freshener of FIG. 1; and,

FIG. 5 is a bottom plan view of the decorative air freshener of FIG. 1.

The broken line showing of lettering in FIGS. 1-4 are for illustrative purposes only and form no part of the claimed design.
